Louis Toth,

INVENTOR

BY Julian J. Wittel

ATTORNEY

UNITED STATES PATENT OFFICE

LOUIS TOTH, OF NEW YORK, N. Y.

COMBINED FOUNTAIN PEN AND BLOTTER

Application filed January 21, 1928. Serial No. 248,237.

This invention relates to improvements in writing pens and more particularly to the well known fountain pen now in general use.

The object of the invention is to provide a chamber mounted in or carried by a writing pen, adapted to normally receive a strip or ribbon of blotting material and having means whereby said strip or ribbon, when partially withdrawn from said chamber, will be automatically returned thereto when released by the fingers.

A feature of the construction resides in providing the usual pen protecting cap of a fountain pen with a rotative member on which a blotter strip is wound, said strip extending through a slot in the side wall of said cap and provided with a clamp bar to arrest the inward movement of said strip, the rotative member being provided with a central pin on which a locking cross head and a ratchet are fixed, and a pair of dogs adopted to engage said ratchet, a spring being coiled around the pin to motorize it when returning the blotter strip within the cap, when the pen is inverted and a pull on said strip is released.

Another feature of the construction is found in a compact clamp bar to provide a limiting stop for blotter strip in its inward spring pulled movement comprising hinged pieces, one having a threaded shank and the other an opening through which the shank passes to receive a nut which construction enables the user to replace blotter strips with great facility.

The rotative member on which the blotter strip is rolled may take the form of a drum having end flanges and longitudinal slots to receive a reduced end of the blotter strip to secure it in place and against relative movement with respect to said drum.

The invention possesses other advantageous features which with the foregoing will be set forth at length in the following description, and it is to be understood that I do not limit myself to the showing made in the appended drawings as I may adopt many variations within the scope of the invention claimed.

In the drawings,
50 Fig. 1 is a side elevation of a fountain pen

including my invention, the cap portion of the pen being in section.

Fig. 2 is a diagrammatic horizontal cross section taken about on the line 2—2 of Fig. 1.

Fig. 3 is an enlarged sectional elevation of 55 a rotative member or drum comprising part of my invention.

Fig. 4 is a top view of the pen cap, with parts omitted.

Fig. 5 is a horizontal cross section taken 60 on the line 5—5 of Fig. 3.

Fig. 6 is an enlarged fragmentary section through the free end of the blotter strip and its clamp bar on the line 6—6 of Fig. 1.

Fig. 7 is a view like Fig. 6, but with the section line taken at 7—7 of Fig. 1.

Fig. 8 is a detail, in side elevation, of the composite clamp bar for stopping the inward movement of the blotter.

Referring to the drawings, my invention is 70 embodied in a fountain pen 10, consisting of the usual barrel or ink container 11, pen point 12 and pen protecting cap or housing 13, providing a chamber 14, above the pen point as shown in Fig. 1 of the drawings. 75

The cap or housing 13 is preferably threaded onto the barrel 11, as at 15, and is closed at the top by a threaded cover 16, and revolvably mounted within said cap is a drum 17, preferably formed of sheet metal. This drum 80 is formed with a hub 18, end flanges 19, a cross wall 20, longitudinal slots 21 in its side and radial slots 22 in its top.

A pin 23, is passed downward through the hub 18 and carries in fixed relation therewith 85 a cross head 24, at the top and a racket 25, arranged just under said hub and said pin is connected at its lower end to one end of a spiral spring 26, which has its other end anchored to the cross wall 20 as at 27. 90

Swinging from cross pins extending across the radial slots 22, at the top of the drum 17 are angular dogs 28, said cross pins being arranged close to the hub 18, so that gravitation will cause both of the dogs to engage the 95 ratchet 25 when the pen is in a vertical position, but when said pen is lying or is held horizontally, at least one of the dogs 28 will engage said ratchet and maintain the spring in charged condition. 100

The blotter 29 is cut away at its inner end to provide a tongue 30 which is threaded through the slots 21 in the drum 17 to make it fast therewith.

5 The cap 13, has a slot 31 through which the blotter is drawn outwardly for use, and to prevent the free end of said blotter from entering said slot I provide a composite clamp bar 32 comprising hinged pieces 33 and 34 the former having a threaded shank 35 passing through a hole 36 in the piece 34 and receiving a ball nut 37 to clamp the parts on the blotter as shown in Figs. 6 and 7 of the drawings.

15 The operation of my device is as follows: When there is a need for using the blotter the same is pulled out to the desired distance where it will remain, as explained hereinbefore. Spring 26 will be tightly wound by 20 this operation and when it is desired to return the blotter, the pen is preferably inverted and a quick slight pull is exerted on the blotter strip whereby the dogs 28 will be released from frictional contact with the shoulders on the ratchet, then the dogs will fall away from the ratchet and the spring will rewind the blotter.

25 What I claim as new is:

1. In a pen having a housing and a drum 30 therein with a blotter wound thereon, a relatively stationary pin journalled in said drum; a spring normally urging said drum to rotate in one direction on said pin; a ratchet wheel secured on said pin, and dogs pivoted on 35 said drum preventing the rotation of the drum under the influence of the spring when engaging each other, but permitting its rotation in the reverse direction; an end wall on said drum having slots therein, said dogs being angular in shape and pivoted on pins in said slots so that under the influence of their gravity they may engage said ratchet wheel or drop back into said slots out of engagement with said wheel, according to the position of 40 the pen.

45 2. In a pen having a housing, a drum with a blotter wound thereon in said housing and a slot in the wall of the housing through which the free end of the blotter is drawn, said drum being under the influence of a spring to normally draw said blotter inwardly through 50 said slot; a detachable clamping stop piece on the free end of the blotter comprising an angular bar, a flat bar to rest in the angle of 55 the other bar, the free end of the blotter being clamped between said two bars, and threaded pins on the flat bar passing through openings in the angle bar and carrying nuts.

60 3. In a pen as set forth in claim 2, said two bars being hinged to one another at the one end of the same.

Signed at New York, in the county of New York, and State of New York, this 7th day of January, A. D. 1928.
